United States Patent Office

Des. 225,087
Patented Nov. 7, 1972

225,087

COMBINED REFLECTIVE HIGHWAY LANE DIVIDER AND ROAD MARKER

Dwight L. Haley, Tyler, Tex., assignor to Ferro
Corporation, Cleveland, Ohio

Filed Feb. 24, 1971, Ser. No. 118,590

Term of patent 14 years

The portion of the term of the patent subsequent to
Feb. 21, 1981, has been disclaimed

Int. Cl. D29—02

U.S. Cl. D72—1

FIG. 1

FIG. 3

FIG. 2

FIG. 4

FIG. 1 is a top plan view of a combined reflective highway lane divider and road marker showing my new design;

FIG. 2 is a front elevation view thereof;

FIG. 3 is a side elevation view thereof; and

FIG. 4 is a perspective view thereof.

This is a continuation-in-part of design application D. 20,850 filed Jan. 9, 1970, and now abandoned.

I claim:

The ornamental design for a combined reflective highway lane divider and road marker, as shown.
